[57] CLAIM

The ornamental design for a drinking straw, as shown and described.

DESCRIPTION

FIG. 1 is a front perspective view of the drinking straw showing my new design;

FIG. 2 is a side elevational view thereof, the remaining
sides being identical;

FIG. 3 is a top plan view thereof; and,

FIG. 4 is a bottom plan view thereof.

FIG. 1

FIG. 2

FIG. 4
